*Design of Bust of Gen Taylor.
By Philip Bartlett
of N. Orleans*

Patented March 28 1848.

N° 172.

Dec. 172

Philip Garboille, a New Orleans, Louisiana,
Letters Patent No. 172 dated March 25th, 1848

9910

The Schedule referred to in these Letters Patent and
making part of the same.

To all whom it may concern:

Be it known that Philip Garboille, of New Orleans, in the
County of and State of Louisiana, has produced a
New Design for a bust of Gen. J. Taylor, and he does hereby de-
clare the following to be a full clear and exact description of the
same, reference being had to the annexed drawings, making apart
of this Specification, in which Fig. 1 is a view of the bust.

I provide a pattern for a bust of Gen. J. Taylor, by model-
ling or otherwise, and from this prepare moulds in the usual way,
for casting duplicates of my pattern.

My pattern is as follows: viz., a head or likeness of
Gen. Taylor placed upon a model neck and chest, these being
placed upon a square and circular base of mounting, as
seen in the drawings hereto annexed.

What I claim and desire to secure by Letters
Patent is the pattern or configuration forming a bust of Gen. Tay-
lor as described and set forth in the annexed Specification and
drawings.
